UNITED STATES PATENT OFFICE.

FRED WITTENMEIER, OF CHICAGO, ILLINOIS.

REFRIGERATING SYSTEM.

Application filed August 28, 1922. Serial No. 584,787.

This invention relates to a new and improved refrigerating system and more particularly to a system for the circulation of cooling fluid in installations in which a plurality of cooling coils are located at separated points.

In modern building construction it has become the practice to supply central refrigerating systems which operate refrigerating coils located at different points throughout the building. The general practice in distributing this fluid has required the use of pipes to carry the fluid to the top of the building and a pair of service pipes connected to each coil or column of coils located approximately vertically above each other on different floors of the building. Of these two service pipes, one has carried the cooling fluid to the coils and the other has served as a return pipe to receive the fluid from the coils and carry it back to the cooling and circulating machinery.

Since these pipes carry a fluid at a temperature very considerably below that of the atmosphere, it is necessary that they be completely covered by substantially heat proof casing. This renders the provision of the two pipes in connection with each series of coils a very considerable expense. Further, the pipes with their covering take up a very considerable amount of space.

It is an object of the present invention to provide a system in which a single service pipe conveys the fluid to a set of coils and the same pipe serves to carry away the fluid from the coils.

It is a further object to provide means whereby the flow of fluid from the service pipe to each coil may be independently regulated.

It is an additional object to provide a system in which the flow of the fluid through the service pipe serves to aid in drawing the fluid from the coils.

It is also an object to provide a system which is simple and requires a minimum amount of pipes and fittings and which may be installed without involving the use of a large amount of wall or partition space.

Other and further objects will appear as the description proceeds.

Broadly, my invention comprises a system involving a plurality of service pipes fed with cooling fluid from above by means of a single large riser. Each service pipe has connected thereto a plurality of coils,

each coil having both ends connected to the same pipe. In the preferred form, adjustable means are provided extending into the service pipe adjacent the entrance to the coil and adapted to control the amount of flow from the service pipe to the coil. The lower end of the coil is preferably connected to the service pipe at an angle sloping downwardly toward the pipe so that flow in the service pipe aids in drawing the fluid through the coil.

I have illustrated a certain preferred embodiment of my invention in the accompanying drawings, in which:

Figure 1 is a somewhat diagrammatic elevation showing the relation of the units in the system;

Figure 2 is an elevation on an enlarged scale showing a single unit;

Figure 3 is a section showing the construction in detail;

Figure 4 is a transverse section taken on line 4-4 of Figure 3.

The cooling fluid is circulated from the tank 7 by means of the pump 8 and forced up the riser 9. From the upper end of the riser 9 it is distributed to the service pipes 10. The lower ends of the service pipes are connected by return pipes 11 to the tank 7. It will be understood that the tank and pump as shown are diagrammatic and that any refrigerating system and circulating means may be used.

The T's 12 are placed in the service pipes 10 and are connected by pipes 13 and fittings 14 to the upper end of the coils 15. The lower ends of the coils 15 are connected through the angle fitting 16 to the service pipe at points below the T's 12. The T 12 has screwed therein the plug 17 which serves to reduce the size of the lateral opening of the T and to secure the pipe 13 therein. Pivoted to this plug 17 at point 18 is the deflecting vane 19. The adjusting rod 20 has one end connected to the vane 19 and the other end passes out through the fitting 14 and is provided with operating button 21. The fitting 14 is provided with the gland 22 adapted to compress the packing 23 to prevent leakage around the rod 20. The packing may also be compressed sufficiently to clamp the rod 20 in adjusted position.

As clearly shown in Figure 4, the deflecting vane 19 is of smaller area than the inner cross sectional area of the T 12 and when in its fully opened position, will serve to

deflect only a portion of the fluid from the service pipe to the coil. The T 12 is preferably recessed at 24 so that when the vane 19 is in its closed position, the service pipe 5 is entirely cleared by the vane. When in this position, the vane is of an area sufficient to substantially close off the entrance of the coil.

In the operation of the system, the cooling fluid will be forced upward to the top 10 of the building through the riser 9 and will be distributed from one riser to a plurality of service pipes 10. These service pipes extend down through the building and a cooling coil will be ordinarily connected to each 15 pipe upon each floor of the building. These risers and service pipes are protected by heat proof sheathing and are normally enclosed in the walls of the building as shown 20 in Figure 2. The pipes 13 and fittings 14 will project out of the wall and the coil 15 will be placed in a refrigerator indicated at 25, which refrigerator may be of any desired construction.

25 In order to secure the desired cooling effect, it will be necessary to make different 30 adjustments of the vanes 19 upon the controlling coils upon different floors connected to the same service pipe. When the proper 35 adjustment is determined, the rod 20 may be clamped in adjusted position by tightening up the gland 22. Since the vane 19 is smaller in area than the opening in the service pipe, it is impossible to by-pass all of 40 the fluid through any one coil. Thus adequate cooling effect is assured the coils located lower in the building even if the upper vanes should be improperly adjusted. Since the fluid flows back to the service pipe 45 at a downwardly extending angle, the effect of the flow down through the service pipe is increased and it will aid in drawing the fluid through the coil.

By the use of this system, the second or 45 discharge pipes commonly associated with each series of coils are entirely eliminated. This accomplishes a very material reduction 50 in the cost of installation of such systems, simplifies the operation and maintenance, and reduces heat losses. By the means of 55 my adjustable vanes, the system can be adequately controlled and proper cooling effect may be given to each coil regardless of its location in relation to other coils.

55 The particular embodiment of my invention illustrated is by way of example only and I reserve the right to make such changes and modifications as come within the scope of the appended claims.

60 I claim:

1. In a refrigerating system, means for 65 circulating a cooling fluid, a riser, a plurality of downwardly extending service pipes connected to the upper end of said riser, return pipes connecting said service pipes to the

circulating means, cooling coils connected at each end to a service pipe and means adapted to deflect a portion of the fluid in the service pipe through the cooling coil.

2. In a refrigerating system, means for 70 circulating a cooling fluid, a riser, a plurality of downwardly extending service pipes connected to the upper end of said riser, return pipes connecting said service pipes to the 75 circulating means, a cooling coil connected at each end to a service pipe and means adjustably extending into the service pipe and adapted to deflect a portion of the fluid in the service pipe through the cooling coil.

3. In a refrigerating system, a service 80 pipe, connections for supplying cooling fluid to said pipe and withdrawing the fluid from said pipe, cooling coils connected at each end to the service pipe, and a deflecting vane 85 adapted to deflect a portion of the fluid in the service pipe to the cooling coil.

4. In a refrigerating system, a service 90 pipe, connections for supplying cooling fluid to said pipe and withdrawing the fluid from 95 said pipe, cooling coils connected at each end to the service pipe, and a deflecting vane hinged in the service pipe adjacent the opening therefrom to the cooling coil and adapted to deflect a portion of the fluid in the service pipe to the cooling coil.

5. In a refrigerating system, a service 100 pipe, connections for supplying cooling fluid to said pipe and withdrawing the fluid from said pipe, cooling coils connected at each end to the service pipe, and a deflecting vane 105 adapted to deflect a portion of the fluid in the service pipe to the cooling coil, means for adjusting the position of said vane and means for maintaining the adjusting means in adjusted position.

6. In a refrigerating system, a service 110 pipe, connections for supplying cooling fluid to said pipe and withdrawing the fluid from said pipe, cooling coils connected at each end to the service pipe, and adjustable means 115 adapted to deflect a portion of the fluid in the service pipe through the cooling coil, said means in one position substantially closing off the entrance from the service pipe to the cooling coil.

7. In a refrigerating system, a service 120 pipe, connections for supplying cooling fluid to said pipe and withdrawing the fluid from said pipe, cooling coils connected at each end to the service pipe, and adjustable means 125 adapted to deflect a portion of the fluid in the service pipe through the cooling coil, said means being less in area than the cross sectional area of the service pipe and adapted in its fully open position to permit flow through the service pipe.

Signed at Chicago, Illinois, this 6th day of August, 1922.

FRED WITTENMEIER.
